SIGNAL LANTERN

Rolla A. Shellabarger, Decatur, Ill., assignor to
Helen C. Marshall, St. Louis County, Mo.

Application September 2, 1937, Serial No. 162,206

1 Claim. (Cl. 240—10.63)

The present invention relates to new and useful improvements in signal devices of the illuminated type and more particularly to a lantern especially adapted for use in railroad service.

- 5 The principal object of the present invention is to provide a lantern which can be normally used for illuminating the way for the trainman and which can be readily converted instantly for use as a signaling lantern.
- 10 Another important object of the invention is to confine both the regulation red lantern and white lantern into one composite structure so that while the trainman will always have a white light to illuminate his way, he can by a slight manipulation convert the lantern into use as a red lantern without at the same time interfering with the white light of the solitary lantern being used to illuminate the trainman's way.

15 Other important objects and advantages of the invention will become apparent to the reader of the following specification.

In the drawings:

Figure 1 represents a vertical sectional view through the lantern.

25 Figure 2 is a bottom plan view of the lantern.

Figure 3 is a cross section on the line 3—3 of Figure 1.

Figure 4 is a fragmentary side elevational view of the upper portion of the lantern.

30 Figure 5 is a top plan view of the contact battery supporting plate.

Fig. 6 is a bottom plan view of the switch contact plate.

Fig. 7 is a fragmentary detailed sectional view 35 through the lower portion of the red shade.

Figure 8 is a fragmentary detailed sectional view on the line 8—8 of Figure 2.

Referring to the drawings wherein like numerals designate like parts, it can be seen that

40 numeral 5 denotes the outside cylindrical case, while numeral 6 denotes the inside cylindrical case. These cases 5—6 are in spaced relation, defining an annular compartment 7 for the reception of the red lantern shade denoted generally by numeral 8.

45 This shade 8 consists of the cylindrical-shaped pane 9 of Celluloid or some other suitable material colored red. This shade is provided with the upper rim 10 and the lower rim 11 and stays 50 12 extend vertically between the upper and lower rims to straighten the shade assembly.

Downwardly flaring leg members 13 extend from the outer case 5 and are connected at their lower ends by the annular rail 14. Downwardly extending guide members 15 depend from

the inner case 6 and terminate at their lower ends adjacent the lower ends of the legs 13, these guide members 15 at their lower ends being provided with pivotal fingers 16 which are swingable to overlap the lower portions of the legs 13 so that openings in the fingers and legs can register and through which registering openings cotter pins or other securing means 17 can be disposed so that these fingers 16 will serve to support the shade 8 against downward displacement. It is preferable that the upper portion of the space 7 be constricted so that when the shade 8 is forced upwardly it will be frictionally retained against re-settling.

55 Numeral 18 denotes the enlarged inverted U-shaped handle which is secured detachably to the case 5 by suitable attaching means 19. The upper portion of the case 5 converges inwardly against the case 6 and a cap 20 is provided which has bayonet slots 21 therein for receiving the pins 22. Inside of the case 6 is the usual battery 23 having the central contact 24 and off-center contact 25 for engagement with the center contact 26 and ring contact 27 on the insulating plate 28. The bottom side of this insulating plate 28 has the bulb engaging pins 29—30 extending from the plates 31—32 thereon. A strap 33 is connected with the center contact 26 and bridges the plates 31—32. Each of the plates 31—32 is provided with a short leg 34. 30 One leg 34 is located in close proximity to the contact 35 while the other leg is located in close proximity to the contact 36. Screw members 37—38 serving as contactors are feedable upwardly through the bottom 39 of the case 6 to 35 bridge either the contacts 34—35 or 34—36 to result in the energization of either one of the lamps 40—41. The lower rim 11 of the shade 8 can have one or more finger tabs 42 thereon to facilitate grasping of the lower portion of the shade and the lowering of the same.

40 Normally the lantern with the shade 8 in elevated position is used as a lantern to light the way for the trackman or other railroad man, but when he needs a red signal light, all that is necessary is to grasp one of the tabs 42 and pull the red shade 8 downwardly. The lantern is now adapted for composite use in that red light will emanate laterally from the shade while white light will be cast downwardly onto the ground 50 to illuminate the way for the workman.

45 While the foregoing specification sets forth the invention in specific terms, it is to be understood that numerous changes in the shape, size and materials may be resorted to without de-

parting from the spirit and scope of the invention as claimed hereinafter.

Having described the invention, what is claimed as new is:

- 5 5 A lantern comprising a cylindrical case having one end open and disposed lowermost and provided with an annular shade chamber opening through the lower end of the case, said chamber tapering towards the upper end of the case,
- 10 10 means for mounting an electric illuminating means in the case, an annular colored shade slideable in the chamber and adapted to frictionally

engage with walls of the chamber when moved fully therein, depending legs on the case and arranged in diverging relation, an annular member connecting the lower ends of the legs and providing a rest, depending guide members on the case inwardly of the legs and spaced therefrom to coact therewith in guiding the shade when moved outwardly of the chamber, and stop fingers pivoted on the guide member and detachably connected with the legs to limit the movement of the shade outwardly of the chamber.
